UNITED STATES PATENT OFFICE.

HERMAN L. SPEICHER, OF NEW YORK, N. Y., ASSIGNOR TO RELIANCE BALL BEARING DOOR HANGER COMPANY, OF NEW YORK, N. Y., A CORPORATION OF NEW YORK.

DOOR-LOCK.

1,085,065.

Specification of Letters Patent. Patented Jan. 20, 1914.

Application filed June 24, 1913. Serial No. 775,612.

To all whom it may concern:

Be it known that I, HERMAN L. SPEICHER, a citizen of the United States, residing on Laramore avenue, Jamaica, in the county of Queens, in the city of New York, in the State of New York, have invented certain new and useful Improvements in Door-Locks, of which the following is a specification, reference being had to the accompanying drawings, forming a part hereof.

This invention relates to door locks designed with reference to their use on sliding elevator doors, and more particularly sliding elevator doors mounted on movable carriers adapted to slide on fixed tracks. In doors of this general character it is usual to provide a latch lock operatively mounted on the carrier itself. This latch lock must, of course, have a suitable connection to permit the convenient operation of the latch by the operator. This connection, however, between the carrier and the door precludes the possibility of removing easily the door from the carrier or from moving the door with respect to the carrier as, for instance, when the door is hingedly or slidably carried on the hangers.

It is the principal object of this invention to improve the construction of door locks used under conditions analogous to those above outlined by providing a connection between the latch lock on the carrier and the operating handle on the door, so that this connection may be broken readily with respect to the hanger and the parts of the connection as readily reunited when the door is returned to its normal position.

In accordance with the invention a lock of the utmost simplicity and cheapness of manufacture is produced and the particular improvements referred to above are such as will admit of the ready application of the lock to doors of any character and the easy manipulation thereof by unskilled operators.

The invention will be more particularly described with reference to the accompanying drawings in which—

Figure 1 is a fragmentary view in front elevation of a sliding elevator door mounted on a carrier and provided with the improved lock, and relatively stationary door. Fig. 2 is a fragmentary detail view of the improved lock showing particularly the provision for the breaking of the connection between the operator's handle and the latch itself. Fig.

3 is a fragmentary detail view of the operator's handle, the same being indicated as mounted on a door. Fig. 4 is a fragmentary view in plan of the latch proper showing the same engaged with the usual coöperating bracket mounted on the door jamb. Fig. 5 is a sectional view taken on the plane indicated by the line 5—5 of Fig. 3 and looking in the direction of the arrows. Fig. 6 is a view in detail of the coöperating parts of the coupling formed in the connecting rod of the door lock and showing the two disengaged. Fig. 7 is a view similar to Fig. 6 but showing a somewhat modified coupling.

While the improved lock is illustrated herein as applied to a single sliding elevator door, as this description proceeds it will appear that the lock is not to be so limited in its application, but will be equally useful when employed in connection with variable speed doors as well as other types now in general use.

In Fig. 1 the entrance to the elevator shaft is shown as being closed by a relatively stationary door *a* hinged, as at *a'*, to the door jamb *b*, and a single sliding door *c* supported through hangers *c'* from a carrier *d* movable, as usual, on a track *e* extending between the jambs *b*, *b*, of the doorway. On the proper jamb *b*, adjacent the upper edge thereof, is fastened a suitable bracket *f* having a nose *f'* adapted to be engaged by a latch *g* mounted on the carrier *d*, and by which the elevator door or doors may be secured in closed position. The operating or connecting rod between the latch *g* and the operator's handle *g'* is constructed in accordance with the present invention of two axially alined members or rods *g²* and *g³*. One of these rods *g²* is mounted on the sliding door *c* adjacent the outer edge thereof, while the other rod *g³* of the connection is mounted on the carrier *d* and has fixedly secured thereto the latch *g*. The lower rod *g²* is normally clutched to the upper rod *g³* as by means of suitable coöperating coupling members *g⁴* carried on the upper end of the lower rod and the lower end of the upper rod respectively. The engagement of the coupling members *g⁴* is normally assured by reason of a suitable spring *h* which may be operatively connected with the lower rod *g²* so as to move the latter upwardly to an extent limited only by either its engagement with the upper rod *g³* or the engagement of

a collar g^6 on the lower end of the lower rod with the guide bracket c^2 therefor.

From the description thus far given it will be evident that the operator may rock the latch g against the action of its torsional retaining spring g^6 so as to disengage the latch from the nose f' of the bracket f on the door jamb b and permit the door c to be slid to open position. When the door c is in open position it will be evident that only half of the shaft entrance is free to be used. It often becomes desirable to open the entire shaft entrance to permit the unloading of unusually bulky articles. Hitherto sliding doors of the general character herein illustrated when provided with locks mounted on the carriers, could not be moved to an angular position with respect to the carriers even though the doors were hingedly supported by their hangers, by reason of the rigid connection between the carriers and the doors constituted by the operating rod for the lock. The present invention eliminates this inconvenience so that when the door c is slid to its open position it may then be swung about the hinge connection c^8 by which it is supported on the supporting bar c^5 carried by the hangers c' to open fully the entrance to the elevator shaft. For instance, the operator need only remove the pin c^4 by which the door c is held in alignment with the supporting bar c^5 , and then draw downwardly the lower rod g^2 against the action of the spring h , thus disengaging the coupling member g^4 of the lower rod from the corresponding coupling member on the upper rod g^8 . The result of this manipulation is that the lower rod g^2 remains supported by the door while the upper rod g^8 as an independent member remains supported by the carrier d . From this explanation it will be understood that the door c is free to be swung about its hinge connection c^8 to an angular position with respect to the carrier d , and open wide the shaft entrance, the relatively stationary door being free to swing open on its hinges a' as will be evident.

If desired, a flange g^7 may be formed on the collar g^6 carried adjacent the lower end of the rod g^2 , to engage with the lower face of the bracket c^2 and hold the lower rod in retracted position against the action of the spring h as long as may be desired. When the door is returned to its normal position and the pin c^4 restored, the operator may release the flange g^7 from the engagement with the bracket c^2 and permit the spring h to move the lower rod g^2 upwardly until the coupling members g^4 are again in secure engagement.

In Fig. 7, the upper rod g^8 is shown as having its lower end beveled, as at g^8 , while the coupling member g^9 mounted on the upper end of the lower rod g^2 is formed in-

teriorly with a corresponding beveled recess g^{10} to receive the beveled end of the upper rod. The advantage of this form of coupling resides primarily in the fact that when the lower rod stands in its normal position and the door c is returned to its normal position in alignment with its supporting bar c^5 , the engagement of the upper rod g^8 with the relatively yielding coupling g^9 will be automatic and without special manipulation by the operator.

As indicated hereinbefore this invention is not limited in its scope to its application to doors of any particular character but may be used wherever it is desirable to employ a door lock which has its operative parts mounted respectively on two or more relatively movable parts.

I claim as my invention:

1. In combination with a carrier, a door mounted thereon and movable with respect thereto, an oscillating latch to control the movement of the carrier and door, a sectional rock shaft for the latch mounted on the carrier and the door, coöperating clutch members carried adjacent the proximate ends of the sections of the rock shaft, said sections being relatively movable axially and adapted to disengage said clutch members solely by said axial movement and without moving the latch, and means to hold the clutch members in engagement normally.

2. In combination with a carrier, a hanger mounted thereon, a door hingedly secured to the hanger, an oscillating latch to control the movement of the carrier, hanger and door, a sectional rock shaft for the latch mounted in part on the carrier and in part on the door, and clutch members carried adjacent the proximate ends of the sections of the rock shaft, said sections being movable relatively in an axial direction immediately upon application of an axial stress to disengage the clutch members solely by said relative axial movement and without releasing the latch and permit the door to be swung about its hinged connection with the hanger.

3. In combination with a carrier, a track on which the carrier is slidable, a hanger mounted on the carrier, a door secured hingedly to the hanger, means to hold the door normally in alignment with the carrier, an oscillating latch to control the movement of the door, hanger and carrier, an operating rod for the latch composed of two sections, one of the sections being mounted on the carrier and the other of the sections being mounted on the door, an operating handle carried by the last named section, clutch members secured adjacent the proximate ends of the sections, and a spring to press the sections toward each other axially and thus hold the clutch members in engagement normally, the sections being movable relatively in an axial direction immedi-

ately upon application of an axial stress to disengage the clutch members solely by said relative axial movement and without releasing the latch and permit the door to be 5 swung on its hinged connection with the hanger.

4. In combination with a carrier, a door mounted thereon and movable with respect thereto, a latch to control the movement of 10 the carrier and the door, an operating rod for the latch composed of two sections, one of the sections being mounted on the carrier and the other of the sections being mounted on the door, the proximate ends of said sections being formed to engage normally, the proximate end of one section being tapered 15 in cross section and the proximate end of

the other section being recessed in cross section correspondingly to receive said tapered end, and a spring to press the sections toward each other axially and hold the tapered end within the recess yieldingly, said sections being movable relatively in an axial direction to permit their disengagement solely by said relative axial movement and 20 without releasing the latch, whereby the door may be moved freely with respect to the carrier.

This specification signed and witnessed this 23rd day of June, A. D. 1913.

HERMAN L. SPEICHER.
